GRINDING APPARATUS

Samuel A. Hamnett, Los Angeles, Calif.

Application August 29, 1938, Serial No. 227,256

5 Claims. (Cl. 51—92)

This invention relates to grinding apparatus.

The general object of the invention is to provide an improved tool grinding apparatus.

A more specific object of the invention is to provide a novel tool grinding machine particularly adapted accurately to produce facets on a die sinking tool.

Another object of the invention is to provide a tool grinding apparatus having novel means to hold, rotate and reciprocate the work in relation to a rotating abrasive wheel.

Another object of the invention is to provide a tool grinding apparatus adapted to produce various shapes and numbers of facets on a die sinking tool.

Another object of the invention is to provide a tool grinding machine having novel means for trueing the abrasive member.

A further object of the invention is to provide novel means for mounting an abrasive wheel.

Other objects and advantages of my invention will be apparent from the following description taken in connection with the accompanying drawings, wherein:

25 Fig. 1 is a top plan view of a tool grinding apparatus embodying the features of my invention;

Fig. 2 is a section taken on line 2—2 Fig. 1;

Fig. 3 is a section taken on line 3—3 Fig. 2;

Fig. 4 is a section taken on line 4—4 Fig. 1;

30 Fig. 5 is a fragmentary rear view of the apparatus shown in Fig. 1;

Fig. 6 is a section taken on line 6—6 Fig. 5;

Fig. 7 is a section taken on line 7—7 Fig. 5;

Fig. 8 is a section taken on line 8—8 Fig. 1; and

35 Fig. 9 is a vertical section through the pivot between the support and sector plate.

Essentially my invention includes a rotative abrasive wheel, means to hold a tool to be ground, and means to impart various relative motions between the wheel and the tool.

40 Referring to the drawings by reference characters I have shown my invention as embodied in a tool grinding apparatus indicated generally at 10. As shown the apparatus 10 includes a base plate 11 having integral therewith a hollow upstanding support 12 with a cross section substantially in the form of a sector of a circle. The support 12 has a plane upper face 13 having suitable strengthening ribs 14 disposed therebelow and further includes a portion 15 laterally extending from the face 13 at the intersection of the bounding radii thereof.

45 Slidably engaging the face 13 is a sector plate 16 pivoted thereto as at 17. As shown in Fig. 9 the pivot 17 includes a pin 18 passing through

the plate 16 and the extending portion 15 and having an enlarged head 19 engaging the plate 16 and a lower threaded portion 20 carrying nuts 21 to hold the plate in engagement with the extending portion 15. A cover plate 22 is positioned above the head 19 and is secured to the plate 16 as by screws 23.

The sector plate 16 has a portion having a reduced radius and a beveled arcuate edge 24 engaged by a clamp member 25 attached to the face 13. As shown in Fig. 4 the clamp 25 includes a dog 26 and has a screw 27 engaging the support 12 and having a square aperture 28 in the head thereof engageable by a key 29.

To move the sector plate 16 a radial handle 30 is provided while the beveled edge 24 may be graduated to indicate the position in which the plate is arranged. Radial wipers 31 and 32 are positioned on the plate 16 and a similar wiper 33 is positioned on the support 12. Each wiper consists of a felt strip 34 secured by a plate 35 and screws 36. The wipers prevent harmful substances such as abrasive dust and chips from entering between the face 13 and the sector plate 16.

45 Disposed upon the sector plate 16 are a pair of ways 40 slidably supporting a bed 41 carrying an electric motor 42 having an abrasive wheel 43 mounted on the shaft thereof. The ways 40 are so positioned that the plane of the wheel 43 remains radial in respect to the sector plate 16 irrespective of the position of the bed 41.

The bed 41 may be moved along the ways 40 by the rotation of a screw 45 supported as at 46 and 47 and engaging a half nut member 48 on the underside of the bed 41. One end of the screw 45 is provided with a bevel gear 49 engaging a similar bevel gear 50 on the lower end of a vertical shaft 51 the upper end of which has a manually operable knob 52. As shown in Fig. 5 the shaft 51 is rotatable within anti-friction bearings 53 positioned within a cylindrical casing 54 attached to the sector plate 16. On the shaft 51 and above the casing 54 is a conical collar 55 engaging the shaft 51 by a set screw 56. It will be seen that rotation of the knob 52 will cause the bed 41 to move upon the ways 40: the position of the bed may be indicated by graduations on the conical collar 55.

50 Positioned on the extending portion 15 I provide an upstanding hollow boss 57 engaged by a plunger 58 carrying at its upper end a chuck assembly 59. The assembly 59 floats on a spring 59' on the plunger 58. Attached to one side of the extending portion 15 are ways 60 engaged

by a slide 61 which is secured adjacent its upper end to the chuck assembly 59. The slide 61 may be fixed in position by a screw 62 threadedly engaging one of the ways 60 and impinging upon a gib 63 engaging the slide 61.

As shown in Fig. 6 the chuck assembly 59 includes a hollow body portion 64 which is split as at 65. With the body portion 64 is a hollow cylinder 66 having an anti-friction bearing 67 disposed within each end thereof. The inner races of the bearings 67 engage a hollow core member 68 within which is disposed a collet 68' having a central bore 69, an externally threaded end 70 and a conical head 71 split in the usual manner as at 72. A manually operable knob 73 engages the threaded end 70 and serves to draw the conical head 71 into a conical bore 74 within the core member 68 closing the collet about a tool 75. The core member 68, including the collet and tool, may be rotated by a disk 76 rigidly attached thereto and having suitable spaced depressions 77 on one face engageable by a ball 78 urged thereinto by a spring 79.

As shown an electric motor 80 is positioned on the base plate 11 within an aperture 81 in the support 12 and rotates a cam 82 through a suitable reduction gearing. The cam 82 engages a roller 83 disposed on the lower end of the slide 61 and when the screw 62 is released reciprocates the chuck assembly 59 and the tool 75 tangentially to the wheel 43.

A device 84 for restoring the truth of the wheel 43 is secured to the sector plate 16 by an upright support 85. As disclosed the device 84 includes a diamond point 86 on an arm 87 attached to a block 88 slidable on a pair of parallel arms 89 secured to the support 85. The block 88 is moved upon the arms 89 by means of a screw 90 operated by a crank and handle assembly 91 as clearly indicated in Figs. 1, 5 and 8. The wheel 43 is brought into engagement with the diamond by means of the sliding bed 41, and the diamond is then fed laterally across the periphery of the wheel, the path of the diamond being parallel to the axis of the wheel.

From the above description it will be seen that I have provided various relative movements between the abrasive wheel and the tool to be ground: the wheel may be moved to and from the tool by the sliding bed 41; the wheel may be pivoted about the tool by rotating the sector plate; the tool may be reciprocated tangentially to the wheel; and the tool itself may be rotated. With this combination of motions a large variety of tool shapes may be conveniently produced.

From the above description it will be apparent that I have invented a tool grinding machine that is highly efficient for its intended purpose.

Having thus described my invention, I claim:

1. In a grinding apparatus, a base plate, a horizontal sector shaped support integral with the base plate, said support having a plane upper face, said support including a laterally extending portion at the intersection of the bounding radii of the sector, a pivot pin passing through said laterally extending portion, a sector plate having a hole therein receiving said pin, a clamp member on said support adapted to hold the sector plate in adjusted position, a bed slidable on said sector plate, a motor on said bed, said motor including a shaft, an abrasive wheel on said shaft and disposed so that the plane of the middle portion thereof is co-incident with the vertical plane which passes through the pivot pin and is parallel with the said one edge, a cylindrical casing on said sector plate, a vertical shaft in said casing, hand operated means for rotating said shaft a horizontal shaft extending from said casing, gear means connecting said shafts, said horizontal shaft including a threaded portion, threaded means on said bed engaging said threaded shaft portions, a boss on said laterally extending portion, ways on said laterally extending portions, a slide engaging said last mentioned ways, a chuck assembly on said last mentioned slide, a plunger slidable on said boss, said chuck assembly engaging said plunger, spring 75

sector plate, a horizontal shaft extending from said casing, means to drive said last mentioned shaft, said last mentioned shaft including a threaded portion, threaded means on said bed engaging said threaded shaft portions, a chuck 5 assembly slidable on said support, a plunger slidable on said support, said chuck assembly engaging said plunger and means to move the chuck assembly.

2. In a grinding apparatus, a base plate, a horizontal sector shaped support integral with the base plate, said support having a plane upper face, a pivot pin on said support at the intersection of the bounding radii of the sector, a sector plate having a hole therein receiving said pin, said sector plate having an arcuate outer edge with one portion having a beveled edge, a clamp member on said support adapted to engage said beveled edge to hold the sector plate in adjusted position, a pair of ways on said sector plate and disposed parallel to one edge of the sector plate, a bed slidable on said ways, a motor on said bed, said motor including a shaft, an abrasive wheel on said shaft and disposed so that the plane of the middle portion thereof is co-incident with the vertical plane which passes through the pivot pin and is parallel with the said one edge, a cylindrical casing on said sector plate, a vertical shaft in said casing, a horizontal shaft extending from said casing, gear means connecting said shafts, said horizontal shaft including a threaded portion, threaded means on said bed engaging said threaded shaft portion, a boss on said support, other ways on said support, a slide engaging said last mentioned ways, a chuck assembly on said last mentioned slide, a plunger slidable on said boss, said chuck assembly engaging said plunger, spring means to float the chuck slide and cam means to move the chuck assembly.

3. In a tool grinding apparatus, a base plate, a horizontal sector shaped support integral with said base plate, said support having a plane upper face, said support including a laterally extending portion at the intersection of the bounding radii of the sector, a pivot pin passing through said laterally extending portion, a sector plate having a hole therein receiving said pivot pin, said sector plate having an annular outer edge with one portion of the outer edge of reduced diameter, said reduced portion having a beveled edge, a clamp member on said support adapted to engage said beveled edge to hold the sector plate in adjusted position, a handle on said sector plate, a pair of ways on said sector plate and disposed parallel to one edge of the sector plate, a bed slidable on said ways, a motor on said bed, said motor including a shaft, an abrasive wheel on said shaft and disposed so that the plane of the middle portion thereof is co-incident with the vertical plane which passes through the pivot pin and is parallel with the said one edge, a cylindrical casing on said sector plate, a vertical shaft in said casing, hand operated means for rotating said shaft a horizontal shaft extending from said casing, gear means connecting said shafts, said horizontal shaft including a threaded portion, threaded means on said bed engaging said threaded shaft portions, a boss on said laterally extending portion, ways on said laterally extending portions, a slide engaging said last mentioned ways, a chuck assembly on said last mentioned slide, a plunger slidable on said boss, said chuck assembly engaging said plunger, spring 75

means to float the chuck slide and cam means to move the chuck slide.

4. In a tool grinding apparatus, a horizontal base, an upwardly extending sector shaped support integral with said base, said support having a plane upper face and having stiffening ribs thereon, said support including a laterally extending portion disposed substantially at the intersection of the bounding radii of the sector, a 10 pivot pin passing through said laterally extending portion and having an enlarged head thereon, a sector plate having a hole therein receiving said pivot pin and its head, a fastening means engaging the lower end of the pivot pin and the lower face of the laterally extending portion, said sector plate having an arcuate edge with one portion of the outer edge of reduced diameter, said portion of reduced diameter having a beveled edge, a clamp member on said support and 15 having a face adapted to engage said beveled edge to hold the sector plate in adjusted position, a handle on said sector plate, wiper members on said sector plate and engaging the support, a pair of ways on said sector plate and disposed parallel to one edge of the sector plate, a bed 20 slidably on said ways, a motor on said bed, said motor including a shaft, an abrasive wheel on the shaft and disposed so that the plane of the middle portion of the cutting periphery thereof is co-incident with the vertical plane which passes through the pivot pin and is parallel with the said one edge, a cylindrical casing on said sector plate, a vertical shaft in said casing, hand oper- 25 ated means for rotating said shaft, a horizontal shaft extending from said casing, gear means connecting said shafts, said horizontal shaft including a threaded portion, threaded means on said bed engaging said threaded shaft portions, a 5 boss on said laterally extending portion, ways on said laterally extending portions, a slide engaging said last mentioned ways, a check assembly on said last mentioned slide, a plunger slideable on said boss, said chuck assembly engaging 10 said plunger, spring means to float the chuck slide and cam means to move the chuck slide.
5. In a tool grinding apparatus, a base, means on the base to support a tool to be ground, a sector plate pivotally mounted on said base with the 15 axis of the pivot substantially co-incident with the tip of a tool on the tool support, a pair of ways on said sector plate, a bed slidably engaging said ways, a motor on said bed, said motor having a shaft, an abrasive wheel on the shaft, 20 the axis of the pivot being disposed between the planes of the faces of the abrasive wheel, a truth restoring member, said member including a support mounted on said sector plate, a pair of parallel arms secured to said support, a reciprocating 25 block mounted on said arms, a cutting point on said block, said block having a threaded aperture, a threaded shaft engaging the threaded aperture in said block, means to rotate said threaded shaft to thereby shift the block, said cutting point 30 being in the path of movement of the abrasive wheel.

SAMUEL A. HAMNETT.
